VAPOR CONDENSING APPARATUS

Henry E. Byer, Bernardsville, N. J.

Application March 27, 1948, Serial No. 17,547

14 Claims. (Cl. 261—24)

1

This invention relates to the condensation of steam and other vapors through use of the barometric type of condenser, and especially to a method and apparatus for improving the operation of the water flow in the barometric pipe employed.

In my prior Patents Nos. 2,013,029 and 2,081,615, I have disclosed improved apparatus of the counter-current and of the parallel flow types. I have now made a further improvement in such barometric condensers, whereby I take advantage of the "dead space" or void, which currently exists between the bottom exit opening of the condenser, through which the waste water and any air, and non-condensable gases as may be cleared therefrom from the condenser, and the top level of the solid column of water riding in the waste barometric pipe, to secure a more efficient method of discharging said waste water, air and non-condensable gases, through said bottom opening of the condenser into the tail pipe. A more efficient method of removing to atmosphere said waste water and said air and non-condensable gases results.

One of the objects of the invention is to achieve greater economies in the operation of a barometric type condenser.

Advantage is taken of the hydraulic ejector action which commercial experience has proved occurs in the bottom of my above mentioned condensers and to provide a tail pipe construction whereby the return or "slip-back" of a portion of the air and non-condensable gases from the above mentioned "dead space" in the waste pipe above the level of the solid water column into condenser head is reduced to such a negligible quantity, commercially speaking, that the existing "vacuum creep" correctly experienced in a vessel being evacuated by my condenser is reduced to a negligible amount. Variation in "slip-back" will cause a change in the vacuum or a so-called "creep." As the gases are carried along by the water stream, there will be a certain amount of said gases slipping back into the condenser, which is known as "slip-back."

A further object brought about by my present invention is a reduction in the auxiliary power required to effect the condensation, both as regards the air removal, and as regards the water removal to the atmosphere when a tail pump is employed to remove the waste water from the tail pipe.

One of the features of the present invention is the connection of a throat piece or tail pipe for receiving the liquid-flow from the condenser and delivering the liquid to a barometric pipe

2

closed at the upper end, and connected to water removal means at its lower end, with a constant level liquid control means provided in conjunction with said barometric tail pipe to maintain a constant liquid level above said exhaust end of the throat piece for sealing the same inside the barometric pipe. A gas collecting chamber is thereby provided at the top end of the barometric tail pipe and a gas removal means connected thereto for maintaining an absolute pressure in said chamber between the absolute pressure in the condenser and atmospheric pressure. The liquid can be removed from the bottom of the tail pipe by various means, such as a pump or by gravitational flow into a seal tank.

These and other objects, features and advantages of the invention will become apparent from the following description and drawings which are merely exemplary.

20 Figure 1 is an elevation partly in section of one form of the invention.

Figure 2 is a sectional view taken along the line 2—2 of Figure 1.

Figure 3 is an elevation partly in section of a modified form of the invention.

Figure 4 is a sectional view taken along the line 4—4 of Figure 3.

Figure 5 is an elevation partly in section of another modified form of the invention.

30 Figure 6 is a sectional view taken along the line 6—6 of Figure 5.

Figure 7 is an elevation partly in section of a modification of the invention.

Figure 8 is a section taken along the line 8—8 of Figure 7.

35 Figure 9 is a fragmentary section of a further modification of the invention.

Figure 10 is an elevation illustrating prior practice.

40 For purposes of comparison, a prior condensing system is found in Figure 10 wherein steam to be condensed enters condenser 10 through steam inlet 11, the injection water entering at 12 and the waste water discharging into the waste pipe 14 through opening 13. A centrifugal tail pump 15 removes the waste water from 14, discharging the same through discharge control valve 16 into an open well 17 and thence to the sewer 18.

45 This construction provides for water discharge valve 16 to open as the water level 19—19 tends to rise, and to close as the water level 19—19 falls. Valve 16 in this case can be a standard make of valve connected by link motion to the float control 21.

50 55 The air and non-condensables are removed from condensers 10 at 22 by an air pump com-

prising a primary jet element 23 and a barometric jet inter-condenser 24 into which water enters at 25. A secondary jet 26 is connected to the inter-condenser. Drain pipe 27 carries the waste water from 24 into waste pipe 14.

With the water level 19-19 maintained as mentioned, the vertical dimension 28 between 13 and 19-19 varies in accordance with the building arrangement. The dimension 29 between the center line of steam inlet 11 and floor level 30-30 varies over a wide range because the pump 15 in current practice is located on the basement floor. Because of building structural requirements, it is necessary to locate the float control and its mechanism well below opening 13.

Such a difference in dimension 29 results in a wide variation in the volume of the dead space 20, as it actually occurs in commercial practice; producing a corresponding wide variation as regards the "vacuum swing" experienced in the vacuum vessel being served by the condenser. It will be apparent that the percentage of air and non-condensables carried into the space 20 will vary with resultant variation in the "slip-back" of air and non-condensables through opening 13 back into condenser, depending on the height of the water fall in 20.

Commercial experience shows a variation in operating results of such a previously used apparatus because of this variation in vertical heights mentioned, employing the same type and design of vacuum vessel to be evacuated, operating under the same condenser operating conditions, and with the same sizes of condensers employed.

The condenser of Figure 10 is of the counter-current design as described in my Patent 2,013,029. Commercial operation has shown that the large diameter hydraulic water cone 31 with the diameter of the casing as its base as at 32 will entrap and carry through the water opening 13 approximately 50% of the non-condensable gases entering condenser, which represents in general the amount which enters through 11 in the steam and through leaks. The balance of the air and non-condensables enter with the injection water at 12 and through leaks. As the water removal pump 15 can carry out but a small percentage of the air and non-condensable gases carried into the dead space 20, it will be apparent that such air and gases must be drawn back into condenser casing 10 through 13 for removal by the air pump through 22. The diameter of the condenser casing 10 and the tail pipe 18 must be made amply large so as to assure a slow air velocity through the condenser because otherwise experience proves that there will be a surge in the vacuum.

If the vacuum carried in the previous type condenser 10 is 27" Hg and 380 G. P. M. water is handled, the current steam jet practice would design the primary jet element 23 to maintain 27" Hg at 22, 22" Hg in the secondary jet element 26, and 22" Hg in the inter-condenser 24. On the basis that 17 pounds per hour of atmospheric free dry air are to be removed from the condenser with 135 pounds per square inch as motive steam power for the jet pump, the primary jet 23 would require approximately 40 pounds per hour motive steam and the secondary jet 26, 49 pounds per hour; or a total of 89 pounds per hour motive steam to operate the steam jet air pump. The temperature of the air at 22 is assumed to be 96° F. and injection water temperature entering at 12 is assumed to be 85° F.

The water pump 15 as illustrated would be designed to operate against a total head of 30 feet

of water with a 9 foot submergence and 27" Hg in the tail pipe 14. When so operating and handling 380 G. P. M. of 110° F. water and based on standard pump efficiencies, the operating horsepower would be approximately 4.28 and a 5 H. P. motor would be required. It is thus seen that in a condenser operated according to the described example of prior practice, that the steam cost to remove the air and non-condensables is 89 pounds per hour and the horsepower required for the motor will be 4.28.

A condenser made in accordance with the present invention is seen in Figure 1 having a tail pump 35 at an elevation 36 similar to elevation 29 of Figure 10. In the invention, advantage of the hydraulic ejector action is used to deliver the air and non-condensable gases discharged by said hydraulic ejector action into a lower vacuum positively maintained in the air collecting space or "dead space" 37. In the form of the invention seen in Figures 1 and 2, the air or gas collecting space or chamber is formed for convenience between the exterior tail pipe 38 and a relatively smaller diameter and shorter throat piece 39 which now forms an improved exit passage for the air and waste water discharging through opening 40 of the condenser 41. The open end 42 of throat piece 39 is sealed below the level 43-43 of the solid column of water 44 maintained in pipe 38, a water column 37' having a height 45 rising to a level 46-46 being maintained in throat piece 39 by the difference in the pressure in "dead space" 37 and the pressure in condenser 41. Condenser 41 may be of the counter-current type illustrated in my prior Patent No. 2,013,029.

In the form seen in Figure 1, with the vacuum in 41 at 27" Hg, the vacuum in 37 would be 22" Hg and a column of solid water 45 of a height of 5.6 feet would balance the difference in the two vacuua. Thus the previous "dead space" shown at 20 in Figure 10 is eliminated between level 43-43 and the exit opening 40. It will be apparent that with the air and non-condensable gases carried down the interior throat piece 39, that said air and gases will be promptly removed at the 22" Hg vacuum state so that only a negligible percentage of the air and non-condensable gases can back into condenser 41 in the present invention. For this reason, the necessity for providing a steam jet pump with a capacity of 17 pounds per hour of atmospheric free dry air, as in Figure 10 in previous practice is eliminated. Instead, the primary element 47 in the form of the invention illustrated in Figure 1 would only be required to evacuate one-half of that amount or 8½ pounds of atmospheric free dry air per hour. This represents a saving of 20 pounds of motive steam which is equal to approximately 20% saving in said power as compared to the device of Figure 10.

By mounting the steam jet intermediate condenser 48 on the side of the tail pipe 38, with two admission ports 49 and 50, it will be apparent that the air and non-condensable gases discharged through the improved inner tail pipe or throat piece 39 through its exit opening 42, will be pulled into the air collecting chamber 37 at a 22" Hg vacuum, and thence through the port 50 into intermediate jet condenser 48 where the air and gases will mingle with the air and gases exhausted into 48 by the primary jet 47 through port 49 for removal to atmosphere by steam jet element 51.

It will be observed that the construction of Figure 1, not only entirely eliminates the "dead

space" above the water level in the tail pipe but the lower vacuum carried in space 37 also permits the attachment of the steam jet vacuum pump arrangement including jet condenser 48 to tail pipe 38, whereby the same lower degree of vacuum carried in space 37 is carried in inter-condenser 48 by secondary jet 51, the primary jet 47 exhausting into the same lower degree of vacuum carried in inter-condenser 48.

By the above improved means, the two stage vacuum pump is now furnished with an inter-condenser 48 which has two admission openings for air and steam. The secondary steam jet element 51 can have the same capacity as mentioned for Figure 10, 17 pounds per hour atmospheric air at 22" Hg vacuum. The primary element 47 can be furnished with a capacity sufficient to handle 8½ pounds per hour at 27" Hg vacuum with a steam consumption of 20 pounds per hour. The secondary jet 51 will require 49 pounds per hour motive steam. The waste water from inter-condenser 48 drains off into tail pipe 38 at 52.

An air control valve 53 or other means can be used to admit atmospheric air into the air collecting chamber should the vacuum in 37 become higher than the specified 22" Hg.

A float control 53 can be connected to valve 54A for controlling the level 43—43. Pump 35 exhausts through pipe 54 to the outlet at 55.

Because the vacuum against which the tail pump 35 now pulls is 22" Hg instead of 27" Hg in Figure 10, the pumping horsepower is reduced to 3.86 H. P. representing a reduction of approximately 14% over the horsepower required to operate the pump as indicated in Figure 10, this calculation being based on the standard calculation employed by all water pump manufacturers.

There is a saving therefore in the horsepower required to operate the tail pump of 14%, and there is a saving of approximately 20% in the amount of steam required to operate the steam jet, over current practice, such as illustrated in Figure 10, the total steam required to operate the jets being only about 69 pounds per hour.

In Figure 3 will be found another form of the improved construction of the invention, wherein the float control mechanism is replaced by an internal sealing tank 60 with pump 78 having a discharge loop comprising pipes 61, 62 and 63. A check valve 64 is located in the discharge line. Pumping level 65—65 thus is maintained below the sealing tank level 66—66.

One of the advantages of this type of construction is that it does not require a float valve mechanism.

In the operation of the arrangement of Figure 3, the water flow through condenser 67 functions as described for Figure 1 but the diameter of the tail pipe 68 is made greater than the diameter of the pipe illustrated in Figure 2, so as to permit the use of a sealing tank 60 of suitable volume.

It will be evident that with the open end 69 of the throat piece 70, sealed below the level 66—66, the open end 69 of said pipe 70 will deliver its contents into the internal sealing tank 60, and function with operating figures as mentioned for Figure 1. There will be a vacuum of 22" Hg carried in gas collecting or "dead space" 71, the air and non-condensable gases being removed from 71 through port 72 into inter-condenser 73 where they mingle with the air and gases carried into inter-condenser 73 by the primary jet 74 through port 75 for removal to 75 at a height above the ground level 95—95, in

atmosphere by steam jet element 76. Water employed in the inter-condenser 73 drains off into sealing tank 60 through port 77.

Referring now to the water removal pump 78, this is shown as a centrifugal pump of the open impeller type with its casing vented by pipe 79 into air collecting chamber 71. With this type of open impeller pump, the pumping efficiency is less than with a double suction type of centrifugal pump illustrated in Figure 1 but the loss in efficiency is compensated for by the discharge loops 61, 62 and 63 illustrated in Figure 3, whereby the horsepower required to remove the water from the tail pipe 68 in general can be considered as the same as with the type of pump shown in Figure 1. The horsepower required to operate the tail pump 78 therefore can be assumed to average 3.86 H. P. and the saving in the amount of steam required to operate the steam jet over current practice is assumed to be 20%. In the arrangement of Figure 3, the power and steam required to operate the auxiliaries, water pump and steam jet, are approximately the same as with Figure 1.

In the operation of the condenser illustrated by Figure 3, there will be a water column 80 in the throat piece 70, said water column being balanced by the vacuum 27" Hg carried in condenser 67 and 22" Hg carried in space 71. With the level 66—66 positively maintained by said fixed sealing tank 60, it will be evident that with the vacuum in space 71 maintained at a stable figure of 22" Hg through air control valve or means 81, the column 80 will be maintained at a fixed value, irrespective of the amount of water being discharged from condenser 67 through opening 82 into the sealing tank 60.

It will be understood that the amount of injection water used in a condenser of this type, based on economical operation is varied to suit the seasonal changes in water temperature over a twelve month operating period. This means the water removal pump 78, which is designed to operate at its maximum with the level 66—66 at the height of pipe 62, will drop its pumping level through a range of height indicated as 83 because a water pump designed to operate at a fixed speed will reduce its suction pumping level as the amount of water is reduced. This variation in the pumping level represented by 83 in no way affects the maintained level 66—66 above it so that the stability of the water column 80 is maintained throughout the entire pumping cycle.

It is thus apparent that Figure 3 represents a construction which provides for a maintained sealing tank level in tail pipe 68 at a point above the maximum pumping level 65—65 and a variable pumping head 83 through which the water removal pump 78 operates.

Figures 5 and 6 illustrate the application of my improved construction to a condenser 90 employing a gravitational fall pipe 91, the latter having two off-set bends to accommodate building structure. This is a construction commonly used and results in air binding of the gases in the fall pipe. My invention overcomes the defect of said air binding in the barometric fall pipe.

In the operation of the condenser illustrated by Figure 5, a vacuum apparatus 92, such as an evaporator or the like, is connected by vapor pipe 93 to a condenser 90 of the parallel flow type as shown in my Patent No. 2,081,615. The vacuum apparatus 90 is supported at floor level 94—94

this instance this height being 44 feet. The operating floor 94—94 supporting the vacuum apparatus 90 is commonly placed at a distance well above the barometric height of 34 feet relative to the floor level 95—95.

Injection water enters the condenser 90 at 96 with the vapor and non-condensable gases entering condenser 90 through 93, the injection water being distributed through the interior of the condenser to suit the construction provided for in my Patent No. 2,081,615, whereby a hydraulic water cone 97 is discharged into the condenser exit opening 98, the mixture of water, air and non-condensable gases discharging through throat piece 99, thence into sealing tank 100, the water overflowing level 101—101 and thence into barometric fall pipe 91 into sewer 102. The pipe 91 is illustrated as offset from the center line of the condenser but it should be apparent that the pipe could be on the vertical center line (not shown) of condenser 90.

It will be noted that the gravity fall pipe 91 replaces the water removal pump illustrated in Figures 1—3, inclusive.

Because condenser 90 is of the parallel flow type with all of the non-condensable gases discharging through opening 98 into the tail pipe 103, there is no necessity for the employment of a primary element steam jet as in Figures 1—3, inclusive, so that it is necessary only to furnish the secondary steam jet element 104, said secondary element 104 maintaining a vacuum of 22" Hg.

An inter-condenser 105 and control valve 106 similar to those described for Figures 1—3, inclusive, can be used.

Still employing the same example as mentioned previously where the injection water handled is 380 G. P. M., vacuum carried in the condenser 27" Hg, vacuum carried in the air collecting space 107 is 22" Hg and on the basis that 17 pounds per hour of atmospheric free dry air are to be removed from the condenser while employing motive steam pressure of 135 pounds per square inch, the secondary jet 104 would then require 49 pounds per hour of motive steam to function. The temperature of air handled by jet 104 is taken as 90° F., the injection water temperature entering the air cooler 105 as at 108 being taken as 85° F.

As the water is removed by gravity fall there is no power required to remove the water, so that the total cost of affecting this method of condensation is only 49 pounds per hour of steam required by the steam jet pump 104.

It will be noted the construction provides a compact, convenient one as regards the supporting of the condenser and the accessibility for the operator. Tail pipe 103 is supported at floor level 94—94 by brackets 109 with the jet cooler 105 projecting above the floor level, whereby the water valve 108 and the valve operating the primary jet 104 are at a convenient location for the pan operator of the vacuum apparatus 92.

While Figure 5 illustrates the parallel current type of condenser as shown in my Patent No. 2,081,615, the tail pipe construction is applicable as well to the counter-current type of condenser as seen in my Patent No. 2,013,029. In the latter case, a primary steam jet would be employed with an inter-condenser and a secondary jet similar to the construction illustrated in Figures 1 and 3, such would require the use of 20 pounds per hour of steam to operate the primary jet and 49 pounds per hour motive steam to operate the sec-

ondary jet, representing a total of 69 pounds per hour required to operate the steam jet for the counter-current type of construction as compared to the parallel flow illustrated in Figure 5.

As an illustration of the elimination of "vacuum creep" back from the condenser into the vacuum apparatus served by it, referring to Figure 5, it is evident that as dehydration proceeds in 92, the liquid level therein gradually falls. With the water column 112 as between 98 and 101—101 maintained at a constant column or height, it will be apparent that there will be no "slip-back" of air or non-condensable gases back from 103 into the condenser 90 and thence through pipe 93 into 92. This stabilizes the dehydration process in 92 permitting the dehydration to proceed more steadily, more quickly and with less attention required on the part of the operator of the apparatus.

It is apparent that the invention can be used for purposes other than condensing steam and that various modifications can be made in the illustrated details without departing from the spirit of the invention except as defined in the appended claims.

Another form of the invention is seen in Figures 7 and 8 where the "dead space" is avoided by connecting a throat piece or tail pipe 116 extending downwardly from the bottom opening 117 of the condenser 115. Steam enters the condenser at 118 and water at 119. A parallel flow condenser also could be used. Throat 116 makes a bend 120 and enters into the side of tail pipe 121 so that the lower end of the throat exhausts into said tail pipe. A partition or receptacle 122 serves to maintain the water level 123—123. The partition 122 may have notches or apertures extending downwardly from the upper wall so as to break up the heavy stream of water flowing over the top thereof. It is seen that the gas collecting chamber is interposed between the two tail pipes and intermediate the condenser and the final discharge of the tail pipe means to the atmosphere.

The primary jet 125 draws air from the top of condenser 115 through pipe 126 and discharges the same through pipe 127 into the tail pipe 121. Secondary jet 128 is connected to gas collecting chamber 136. A pump 129 can be employed to remove water from the bottom of tail pipe 121, said pump discharging to waste at 130. The liquid in the condenser will flow down the walls and form a cone of water 131 which flows into throat piece 116. The liquid weight flowing into said throat piece or pipe will remove a large percentage of the air and non-condensable gases from the condenser. The remainder of the air and non-condensable gases in the illustrated counter-current condenser will be removed by primary jet 125. The steam jet discharges into space 132 above the water level 133—133, the steam being condensed by contact in this water sheet or film 134. Said gases pass upwardly through the open slots formed in the water film 134 into gas collecting chamber 136 and thence to the secondary jet 128. It is thus apparent that the water film 134 which is broken up by the slots in the partition 122 will serve to condense the exhaust steam from jet 125 and as a cooling means for the air and non-condensable gases discharged into tail pipe 121.

The column of water 129A will be substantially constant. An air relief valve 131A can be employed to assist the steam jet 128 in con-

trolling the pressure in gas collecting chamber 136.

The straight passage throat piece 116 of Figure 7 can be replaced by a Venturi-type throat piece 135 such as seen in Figure 9 if desired.

The particular arrangement of the tail pipe and throat piece of Figures 1-5, inclusive, can take various forms, it being evident that the tail pipe itself does not necessarily have to be connected directly to the condenser, the main requisite being the provision of gas collecting chamber at the top thereof for removal of gases.

It is thus apparent that the invention discloses a manner of removing air and non-condensable gases from a condenser into a throat piece. The bottom end of said throat piece has a level of liquid maintained at a predetermined point above the end of said throat piece. The gas collecting space over said maintained level of water has air and non-condensable gases removed therefrom at a pressure which is between that in the condenser and the atmosphere. The lower end of the tail pipe in the various forms has suitable liquid removal means such as a pump or a barometric fall pipe discharging through a seal to atmosphere.

I claim:

1. In a direct contact condenser wherein air and non-condensable gases are removed by liquid weight through an aperture in said condenser, a barometric tail pipe with a closed gas collecting chamber at its upper end, liquid removal means connected to the lower end of said tail pipe, a throat piece connected to the bottom of said condenser, and having its lower end exhausting into said tail pipe, constant liquid level sealing means interposed between the lower exhaust end of said throat piece, and said gas collecting chamber, gas removal means connected to said condenser, and gas removal means connected to said gas collecting chamber, said removal means maintaining an absolute pressure therein between the pressure in the condenser and atmospheric pressure, said throat piece maintaining a column of liquid balancing the pressure differential between said condenser and said gas collecting chamber.

2. In a direct contact condenser wherein at least a portion of the air and non-condensable gases are removed by liquid weight through an aperture in the bottom of said condenser, a barometric tail pipe having a closed upper end, said closed upper end defining a gas collecting chamber, a throat piece connected to the bottom of said condenser and having its lower end exhausting into said tail pipe, a constant level liquid sealing means adjacent the exhaust end of said throat piece and adapted to seal the same relative to said chamber, liquid removal means connected to the lower end of said tail pipe, gas removal means connected to said condenser, and gas removal means connected to said gas collecting chamber and maintaining an absolute pressure therein between that in said condenser and that in the atmosphere, said throat piece maintaining a column of liquid balancing the pressure difference between said condenser and said gas collecting chamber.

3. In a direct contact condenser wherein at least a portion of the air and non-condensable gases are removed by liquid weight through an aperture at the bottom of said condenser, a barometric tail pipe having a closed upper end, said closed upper end defining a gas collecting chamber, a throat piece connected to the bottom

of said condenser and to said tail pipe, said throat piece having an outlet in said tail pipe intermediate the upper and lower ends of said tail pipe, a constant level liquid sealing means at the outlet of said throat piece in said tail pipe for sealing said throat piece relative to said gas collecting chamber, liquid removal means connected to the lower end of said tail pipe, and gas removal means connected to said gas collecting chamber and maintaining an absolute pressure therein between that in said condenser and that in the atmosphere, said throat piece maintaining a column of liquid balancing the pressure differential between said condenser and said gas collecting chamber.

4. In a direct contact condenser wherein at least a portion of the air and non-condensable gases are removed by liquid weight through an aperture in the bottom of said condenser, a barometric tail pipe having a closed upper end, said closed upper end defining a gas collecting chamber, a throat piece at least partially in said tail pipe and connected to the bottom of said condenser and to said tail pipe, a receptacle in said tail pipe into which said throat pipe exhausts, said receptacle maintaining a constant liquid level sealing the end of said throat piece relative to said gas collecting chamber, liquid removal means connected to the lower end of said tail pipe, and gas removal means connected to said gas collecting chamber and maintaining an absolute pressure therein between that in said condenser and that in the atmosphere, said throat piece maintaining a column of liquid balancing the pressure difference between said condenser and said gas collecting chamber.

5. In a direct contact condenser wherein at least a portion of the air and non-condensable gases are removed by liquid weight through an aperture in the bottom of said condenser, a barometric tail pipe having a closed upper end, said closed upper end defining a gas collecting chamber, a throat piece at least partially in said tail pipe and connected to the bottom of said condenser and to said tail pipe, a receptacle in said tail pipe into which throat piece exhausts maintaining a constant liquid level above the opening of said tail pipe to seal the end thereof relative to said gas collecting chamber, liquid removal means connected to lower end of said tail pipe, gas removal means connected to the top of said condenser exhausting into said tail pipe below said receptacle and above the normal water level therein, said gases travelling upwardly past the liquid flowing downwardly out of said receptacle, a second gas removal means connected to said gas collecting chamber maintaining an absolute pressure therein between that in said condenser and that in the atmosphere, said throat piece maintaining a column of liquid balancing the pressure difference between said condenser and said gas collecting chamber.

6. In a direct contact condenser wherein air and non-condensable gases are removed by liquid weight through an aperture in the bottom of said condenser, a barometric tail pipe with a closed gas collecting chamber at its upper end, liquid removal means connected to said tail pipe, a throat piece connected to the bottom of said condenser and having its lower end exhausting into said tail pipe, said throat piece including a Venturi-shaped passage therein, constant level sealing means interposed between the lower end of said throat piece and said gas collecting chamber.

11

ber, and gas removal means connected to said gas collecting chamber and maintaining an absolute pressure therein between that in the condenser and that in the atmosphere, said throat piece balancing the pressure and said gas collecting chamber.

7. In a device of the character described, the combination comprising a condenser, a tail pipe connected to the lower end of said condenser, a throat piece connected to the lower end of said condenser extending within said tail pipe and forming a gas collection chamber in conjunction with said tail pipe, means maintaining a predetermined water level below the bottom end of said condenser and above the lower end of said throat piece, gas removal means connected to said gas chamber formed between said tail pipe and said throat piece, and water removal means connected to said tail pipe.

8. In a device of the character described, the combination comprising a steam condenser, a tail pipe connected to the lower end of said condenser, a throat piece connected to the lower end of said condenser extending downwardly within said tail pipe and forming a gas collection chamber in conjunction with said tail pipe, liquid removal means connected to said tail pipe, float control means connected to said liquid removal means and with said tail pipe to maintain a liquid level in said tail pipe above the bottom end of said throat piece, and gas removal means connected to said gas collection chamber.

9. In a device of the character described, the combination comprising a direct contact steam condenser having an aperture adjacent the bottom portion thereof, said condenser having a casing defining the path of a gaseous medium, liquid supply means for said casing, means in said casing distributing said liquid in a downwardly flowing film away from the sides of the casing into the lower end of said casing, a throat piece connected to the lower end of said casing into which said downwardly flowing film is directed, a barometric tail pipe in which said throat piece exhausts, said tail pipe having a gas collection chamber at its upper portion, constant liquid level control means connected with the end of said throat piece for maintaining a predetermined liquid level above the lower end of said throat piece so as to seal said throat from said gas collecting chamber, gas removal means connected to the upper portion of said tail pipe, said gas removal means maintaining an absolute pressure between the absolute pressure in said condenser and atmospheric pressure, and means to remove liquid from said tail pipe.

10. In a device of the character described, the combination comprising a casing defining the path of a gaseous medium, liquid supply means for said casing, means in said casing distributing said liquid as a downwardly flowing film away from the sides of the casing into the lower end of the casing, a throat piece connected to the lower end of said casing into which said downwardly flowing film is directed, a tail pipe connected to the lower end of said casing, said tail pipe being spaced from and surrounding said throat piece, float control means for maintaining a predetermined liquid level in said tail pipe above the lower end of said throat piece, gas removal means connected to the passage formed between the tail piece and the throat piece, said vacuum being maintained between the vacuum in the condenser and atmospheric

12

pressure, and means to remove liquid from said tail pipe.

11. In a device of the character described, the combination comprising a condenser, a tail pipe connected to the lower end of said condenser, a throat piece connected to the lower end of said condenser extending downwardly within said tail pipe and forming a gas collection chamber in conjunction with said tail pipe, means positively maintaining a predetermined liquid level above the lower end of said throat piece forming a liquid barometric leg in said throat piece, said leg balancing the difference in pressure between the pressure in the condenser and the pressure in the gas collection chamber, and gas removal means connected to said gas collection chamber maintaining a vacuum therein between that in the condenser and atmospheric pressure.

12. In a device of the character described, the combination comprising a direct contact counter flow steam condenser having an inlet for the gaseous medium to be condensed and a water inlet, baffle means distributing the water and producing a conical flow of water through the condenser, a barometric tail pipe, a throat piece connected to the bottom of said condenser and exhausting into said tail pipe, said throat piece receiving the conical flow of water through said condenser, a gas collecting chamber at the top of said tail pipe, gas removal means connected to said gas collecting chamber maintaining an absolute pressure in said chamber between the pressure in the condenser and atmospheric pressure, means maintaining a level of water in the tail pipe above the end of said throat piece, and means removing liquid from said tail pipe.

13. In a device of the character described, the combination comprising a direct contact counter flow condenser having an inlet for the gaseous medium to be condensed and a water inlet, baffle means distributing the water and producing a conical flow through the condenser, a tail pipe connected to the lower end of said condenser, a throat piece connected to said condenser within said tail pipe and forming a space therebetween, said throat piece receiving the conical flow of water through said condenser, gas removal means connected to the space between the tail pipe and throat piece maintaining an absolute pressure in said space between the pressure in the condenser and atmospheric pressure, means maintaining a level of water in the tail pipe below the tail pipe connection with the condenser and above the end of said throat piece, whereby the vacuum maintained in the space between the tail pipe and throat piece is sealed relative to the pressure in the condenser.

14. In a direct contact condenser wherein air and non-condensable gases are removed by liquid weight through an aperture in said condenser, a first tail pipe with a closed gas collecting chamber at its upper end, liquid removal means connected to the lower end of said tail pipe, a second tail pipe connected to the bottom of said condenser, and having its lower end exhausting into said first tail pipe, constant liquid level sealing means interposed between the lower exhaust end of said throat piece, and said gas collecting chamber, and gas removal means connected to said gas collecting chamber, said removal means maintaining an absolute pressure therein between the pressure in the condenser and atmospheric pressure, said second

tail pipe maintaining a column of liquid balancing the pressure differential between said condenser and said gas collecting chamber.
